CHRISTMAS ORNAMENT OR SIMILAR ARTICLE

Alfred A. Flaster, New York, N.Y.

Application March 31, 1958, Serial No. 50,235

Term of patent 3½ years

(Cl. D29—1)

Fig. 1 is a front elevational view of a Christmas ornament or similar article showing my new design;

Fig. 2 is a top plan view thereof; and

Fig. 3 is an end elevational view thereof.

The stippling indicates spangles.

The back of the article is substantially the same in appearance as the front.

I claim:

The ornamental design for a Christmas ornament or similar article, substantially as shown and described.
